UNITED STATES PATENT OFFICE.

ALLEN W. JONES, OF OMAHA, NEBRASKA.

MOP-WRINGER.

SPECIFICATION forming part of Letters Patent No. 726,692, dated April 28, 1903.

Application filed October 24, 1902. Serial No. 128,585. (No model.)

To all whom it may concern:

Be it known that I, ALLEN W. JONES, a citizen of the United States of America, residing at Omaha, in the county of Douglas and State of Nebraska, have invented certain new and useful Improvements in Mop-Wringers, of which the following is such a full, clear, and exact description as will enable others skilled in the art to which it appertains to make and use the same, reference being had to the accompanying drawings, forming a part hereof.

The object of this invention is to provide a mop-wringer of simple construction which will be automatic in its operation. This object is attained by the use of the device illustrated in the accompanying drawings; and the invention consists in certain novel features of the same, as will be hereinafter first fully described and then particularly pointed out in the claims.

In the drawings just mentioned, Figure 1 is a side elevation of a mop-wringer embodying the invention and applied to a bucket in operative position, the bucket being partly broken away. Fig. 2 is a vertical section of the same, showing the mop being drawn through the wringer; and Fig. 3 is a detail perspective view of the operating-arms and their connections.

The bucket A is of the usual construction, except that it is provided with feet or rests B on its outer side at its bottom. Across the top of the bucket I secure, by any convenient means, parallel bars C, which support the wringer. Secured and extending between these supporting-bars at one end of the same is a rod D, the ends of which project slightly beyond the sides of the said bars, and on the said rod between the supporting-bars is pivotally hung a bail or hangers E, between the lower ends of which is mounted one of the wringing-rolls F. On the ends of the rod D is pivoted a U-shaped frame or lever G, the base or shouldered portion of which bears against the outer edges of the hangers E, so that when the said lever or frame is swung on its pivot the motion will be transmitted directly to the hangers and the roller swung in the arc of a circle. To the shoulder or base portion of the U-shaped frame or lever I secure the arms H, which project inwardly

over the roller and have their ends turned slightly downward, as clearly shown. The ends of the U-shaped lever or frame are connected by links I with a sliding loop J, mounted on the supporting-bars and bearing against hangers K, similar to the hangers E and having a wringer-roll L mounted in their lower ends. The hangers K are pivotally mounted on a transverse rod M, which passes through slots N in the supporting-bars, near the ends of the same, and has its ends bent inwardly and formed into or provided with hooks or eyes O, which are engaged by springs P, the opposite ends of the springs being secured on the ends of the rod D.

The construction and arrangement of the several parts being thus made known, the operation of the device will be readily understood. The wringer-rolls normally hang downward, as shown in Fig. 1, leaving a free space for the entrance of the mop, the parts on the far side being omitted for the sake of clearness. After the mop has become saturated the handle is placed between the arms of the operating-lever and drawn upward, the operator's feet being placed on the rests B to hold the bucket steady. Only one of these feet is shown in the drawings; but it will be understood, of course, that a similar foot is attached to the opposite side of the bucket. The upward movement of the mop-handle draws the bail or mop-head against the arms H, so that the continued movement of the mop will cause the said arms to swing upward and vibrate the operating-lever G. The movement of the lever G causes the hangers and adjacent roll to swing upward and inward under the influence of the shoulder portion of the lever, while the ends of the lever acting through the links I draw the sliding loop toward the coacting roll and against the hangers K, so as to cause the said roll to swing inward and upward toward the opposite roll. The rolls are thus brought together against the opposite sides of the mop, so that the surplus water will be forced therefrom as the mop is drawn upward from the bucket. The springs P serve to hold the rolls firmly against the mop, while they at the same time permit the rolls to yield to the thickness of the mop, and thereby prevent any clogging which would interfere with the withdrawal of

the mop from the bucket. After the mop is withdrawn the rolls return to their normal positions under the influence of their own weight.

5 It will be obvious from the foregoing description, taken in connection with the accompanying drawings, that I have provided a simple and efficient mop-wringer which leaves the hands of the operator free to handle the 10 mop, the operation of withdrawing the mop from the bucket serving to operate the wringer. The hands of the operator are not employed in the operation of the wringer nor is it necessary to place them in the water or 15 on the wet mop.

Having thus described my invention, what I claim, and desire to secure by Letters Patent, is—

1. A mop-wringer comprising normally separated vibratory wringer-rolls and means operated by the withdrawal of the mop to cause the rolls to approach each other and bear against the mop.

2. A mop-wringer comprising vibratory hangers carrying wringer-rolls, a lever and connections adapted to vibrate the hangers to cause the rolls to approach each other, and means for operating said lever by the withdrawal of the mop.

3. In a mop-wringer, the combination of the hangers carrying wringer-rolls, a slidable loop

bearing against one of the hangers, an operating-lever bearing against the other hanger, connections between the loop and the lever, and arms projecting from the lever over the 35 adjacent roll and adapted to be engaged by the mop.

4. In a mop-wringer, the combination of supporting-bars provided with longitudinal slots near one end, a pivot or fulcrum rod mounted 40 in said slots and having hooks at its ends, a pivot or fulcrum rod secured in the opposite ends of the supporting-bars, springs secured on the ends of said pivot-rod and engaging the eyes at the ends of the first-mentioned 45 pivot-rod, hangers on said pivot-rods carrying wringer-rolls, a lever fulcrumed on the last-mentioned pivot-rod and provided with arms projecting over the adjacent wringer-roll, the said lever bearing against the hanger 50 carrying that roll, a slidable loop mounted on the supporting-bars and bearing against the hangers carrying the coacting roll, and connections between the said lever and said loop.

In testimony whereof I have signed this 55 specification in the presence of two subscribing witnesses.

ALLEN W. JONES.
